UNITED STATES PATENT OFFICE.

ANDREW RASMUSSEN, SR., AND ANDREW RASMUSSEN, JR., OF RIDGWAY, COLORADO.

ADVERTISING DEVICE.

1,375,260.

Specification of Letters Patent. Patented Apr. 19, 1921.

Application filed September 30, 1920. Serial No. 413,781.

To all whom it may concern:

Be it known that we, ANDREW RASMUSSEN, Sr., and ANDREW RASMUSSEN, Jr., citizens of the United States, residing at Ridgway, in the county of Ouray, State of Colorado, have invented a new and useful Advertising Device; and we do hereby declare the following to be a full, clear, and exact description of the invention, such as will enable others skilled in the art to which it appertains to make and use the same.

The invention relates to advertising devices and has for its object to provide a device of this character comprising a base having longitudinally disposed thereon an endless screen having a scene thereon and to provide a rotatable sign display above the endless seam, which sign display is intermittently changed by mechanism operated from the driving mechanism for the the endless scene. Also to provide a figure of a man having pivoted arms, which arms are caused to move in a pointing position in relation to a changing sign by the mechanism which operates the changeable sign.

A further object is to provide spring means for holding the pivoted arms in extended positions.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a front elevation of the device.

Fig. 2 is a detail perspective view of the operating mechanism for the changeable sign and the pivoted arms of the figure.

Fig. 3 is a perspective view of the rear side of the figure, showing the operating mechanism for the arms thereof.

Referring to the drawings, the numeral 1 designates the base of the device and 2 a drive shaft operated by a motor or other source of power, which shaft is provided with a worm 3 which meshes with a gear 4. The gear 4 is carried by a roller 5 and around which roller 5 and a roller 6 an endless scenic belt 7 passes, which belt moves

at all times. Rotatably mounted in bearings of the base 1 is a shaft 8, which shaft is belted to the shaft 2 by means of pulleys 9 and 10 around which pulleys a belt 11 passes. It will be seen that as the shaft 2 rotates the pulley 9 will also rotate thereby causing the shaft 8 to rotate. The shaft 8 is provided with a pulley 12, which pulley is belted to a pulley 13 carried by the lower end of the roller 6, which will cause said roller to rotate at the same time the roller 5 is rotating. Slidably mounted in bearings of the upwardly extending background 14 is a rod 15, the lower end of said rod being disposed above a cam 16 carried by the shaft 8, which cam as it rotates in the direction of the arrow α engages the lower end 17 of the slidable rod 15 and causes said slidable rod to move upwardly. The downward movement of the rod 15 being limited by a stop 18 so that the cam 16 as it rotates will come into engagement with the end 17. The upper end of the slidable bar 15 engages the teeth of a ratchet wheel 19 and causes said ratchet wheel to be intermittently rotated. The ratchet wheel 19 being prevented from retrograde movement by the spring actuated pawl 20, said ratchet wheel 19 is secured on a shaft 21, which is rotatably mounted in bearings 22 of the sides of the frame 23. Rotatably mounted in bearings 24 of the frame 23 is a preferably triangular shaped display sign reel 25 on the pindle 26 of which a disk 27 is secured. The reel 26 is adapted to be intermittently rotated so that signs carried thereby will be brought into registration with openings 28 in the background 14. The revolving of the disk 27 is accomplished by means of an arm 29, which as it rotates engages the pivoted arm 30 and causes its end 31 to move upwardly on the pivotal point 32 thereby causing an upward movement of the arm 33. The arm 33 having its end in engagement with the headed lug 34 will cause the disk to be rotated at the same time the headed lug 34 moves downwardly out of engagement with the notched end 35 of the pivoted arm 36, there being a slight downward movement of the pivoted arm 36 at its end 37, the object of which will presently appear. It will be seen that as the disk 27 is rotated by the arm 33 the display sign which registers with the open-

ings 28 in the background will be changed to a different sign. Arms 33 and 36 are secured together by means of a coiled spring 39 which normally holds said arms in engagement with the headed lugs on the disk 27. After each operation of the arms 33 and 36, said arms are brought to normal position as shown in Fig. 2 by means of the coiled spring 40, which coiled spring is connected to the pivoted lever 31 as at 41 and to the frame work 23 as at 42.

Secured to the upper end of the background 14 as at 43 is a rectangular shaped support 44, to which support is secured the figure of a clown 45, the arms 46 of which are pivotally connected as at 47 and are adapted to be moved downwardly and inwardly so that the hands 48 will point to the signs being displayed in the openings 28 at the moment of change of the signs thereby attracting attention to the signs being displayed and intermittently changed. The arms 46 are normally held in lowered position as shown in Fig. 1 by means of bowed springs 49, one end of said springs being secured to the upper end of the upright 44 and the other ends of said spring secured to the arms 46 as at 50 and at points outside of the pivotal points of the arms 46. Springs 49 normally hold the arms 46 in lowered position. However when the arm 36 moves downwardly incident to the rocking action of the lever 30 the end 51 of a rockable lever 52 is pulled downwardly by the link connection 53. When the end 51 of the lever 52 moves downwardly, the end 54 of said lever moves upwardly and as the end 54 is pivotally connected as at 55 to a rockable lever 56 carried by the upright 44, it will be seen that the ends 57 of the lever 56 will be forced downwardly thereby causing a downward movement through the medium of the connecting links 58 of the inwardly extending arm projections 59, thereby causing the arms 46 to rise after they have been forced downwardly into pointing position by the springs 49.

From the above it will be seen that an advertising device is provided, wherein a movable scenic screen is constantly moved, and one wherein changeable display signs are intermittently changed and attention attracted to the changing signs by pivoted arms, which arms and signs are operated from a single source of power, which source of power also operates the endless scene.

The invention having been set forth what is claimed as new and useful is:—

1. An advertising device comprising a longitudinally disposed endless scene, a back ground rising upwardly, a rotatable sign disposed behind said back ground and adapted to be rotated for positioning various signs in registration with openings in the back ground; a horizontally disposed shaft disposed below the rotatable sign, means for intermittently rotating said shaft, a figure disposed above the rotatable sign and provided with pivoted arms, and means whereby as the shaft is intermittently moved the rotatable sign will be intermittently moved and the pivoted arms of the figure moved in the direction of the sign openings in the back ground.

2. The combination with an endless scene advertising device, of a rotatable sign intermittently rotated for displaying various signs, of means operated by the operating mechanism of the endless scene device whereby the sign will be intermittently rotated and a figure disposed adjacent the rotatable sign and provided with pivoted arms and means whereby the pivoted arms will be simultaneously moved incident to the rotation of the sign.

3. The combination with an endless scene advertising device, of a rotatable display sign intermittently rotated, means operated by the operating mechanism of the endless scene for intermittently rotating the sign, pivoted members pivoted at points above the sign, and means whereby the pivoted members will be pivoted downwardly in the direction of the sign simultaneously with the intermittent rotation thereof.

4. The combination with a horizontally disposed rotatable sign, of a figure disposed adjacent said sign and provided with pivoted arms, spring means for normally holding said arms away from the sign and means whereby the sign may be intermittently rotated and the pivoted arms moved in the direction of the sign against the action of their springs.

In testimony whereof we have signed our names to this specification in the presence of two subscribing witnesses.

ANDREW RASMUSSEN, Sr.
